ATTORNEY

UNITED STATES PATENT OFFICE.

ALBIN E. SHODIN, OF SEATTLE, WASHINGTON.

CONVEYING APPARATUS.

1,316,868.

Specification of Letters Patent. Patented Sept. 23, 1919.

Application filed May 26, 1919. Serial No. 299,800.

To all whom it may concern:

Be it known that I, ALBIN E. SHODIN, a citizen of the United States, residing at Seattle, in the county of King and State of Washington, have invented certain new and useful Improvements in Conveying Apparatus, of which the following is a specification.

This invention relates to elevated conveying apparatus, and more especially to carriers which are employed upon a cable way for the purpose of supporting the ropes leading to and from a load carriage.

The object of my invention is the provision of a rope-carrier which will be of inexpensive and durable construction and provided with devices for propelling the same at a speed having a definite ratio to the speed of the associated load carriage.

With these ends in view, the invention consists in the novel construction, arrangement and combination of parts as will be hereinafter described and claimed.

In the accompanying drawings, Figure 1 is a side elevational view of an elevated conveying system with devices embodying my invention applied thereto. Fig. 2 is a longitudinal vertical section of a rope-carrier, said section being taken through 2-2 of Fig.

4. Fig. 3 is a view partly in side elevation and partly in section, the section being taken substantially through 3-3 of Fig. 4. Fig. 4 is a section through 4-4 of Fig. 3.

Referring to Fig. 1, the numeral 5 represents a track cable which, in the illustrated example, is supported by head and tail masts 6 and 7. Mounted upon said track cable is a load-carriage 8 and wheeled rope carriers 9.

Connected to opposite ends of the carriage 8 are the ends 10 of a traction rope having hauling and return leads 11 and 11¹ respectively, which are guided by pulleys 12 to a drum 13 about which the traction rope 14 is wound as usual. 14 represents a hoisting fall extending from a winding drum 15 over a pulley 16 on the head mast 6, thence over spaced guide pulleys 17 in the load carriage to have its end 14¹ secured to the tail mast 7. The hoisting fall between the pulleys 17 extends downwardly in the form of a bight which carries the fall block 18 to which loads are attached.

Referring now to Figs. 2, 3 and 4, a carrier is formed of a frame having two side plates 19 and 20, in the upper portions

of which are journaled the axles 21 and 22 of grooved wheels 21¹ and 22¹ which are mounted on the cable 5.

Subjacent to the wheel 21¹ is a peripherally grooved sheave 23 which is keyed or otherwise secured to a transverse shaft 23¹ which is also journaled in said frame plates. The sheave 23 serves as a support for the respective hauling rope lead 11, the same being wound as at 11², Figs. 2 and 4 about the sheave one or more times to afford sufficient frictional engagement therewith to effect the rotation of the latter for propelling the carrier, when such hauling line is actuated, by employing the wheel 21¹ as a traction wheel upon the cable 5. For which purpose the shaft 23¹ and axle 21 are operatively connected by means of a train of spur gears consisting, as shown in Figs. 3 and 4, of a pinion 24 and a gear 25 respectively secured upon the shaft 23¹ and axle 21, and an intermediate gear 26 rotatable upon a stub shaft 26¹. The ratio between the teeth of the pinion 24 and the gear 25 is proportional to the speed at which a carrier 9 is intended to travel with respect to the load carriage to maintain the former at a distance from the carriage to suitably support the aforesaid rope and fall.

In the illustrated example (Fig. 1) where but two carriers are utilized, each carrier should operate at approximately midway between the load-carriage and the adjacent mast, thereby requiring the driven gear to be of twice the pitch diameter of the pinion. 27 represents a grooved sheave located, preferably, at the rear of the carrier frame for supporting the return lead 11¹ when the latter is slack. 28 represents a sheave 95 rotatably mounted in the lower part of the frame for supporting the fall rope 14.

The train of gearing for a carrier is desirably inclosed in a casing 29 to protect the same from injury and to exclude dirt. 30 represents a roller disposed within the frame below the wheel 22¹ and subjacent to the cable 5 for the purpose of preventing the adjacent end of the frame being tilted up when the carrier is being propelled in the direction of the arrow in Fig. 2.

The construction and operation of the invention will, it is thought, be understood from the foregoing description.

What I claim, is—

1. In apparatus of the class described, the combination with a track cable, a load

carriage, a hauling rope therefor, and a load hoisting fall, of a fall carrier having a wheel mounted for travel upon said track cable, a pulley provided in the carrier for supporting said fall, a sheave provided in said carrier and about which said hauling rope is wound, gear connections between said sheave and the wheel for driving the latter to propel the carrier when the sheave is turned through the instrumentality of said rope.

2. In apparatus of the class described having a track cable, a load-carriage thereon, a hauling-rope for said carriage, and a fall extending to the carriage, of a fall-carrier comprising a frame having two wheels mounted on said cable, a grooved

sheave provided in the frame and about which said hauling-rope is wound to afford frictional engagement for effecting the rotation of said sheave when the rope is actuated to haul the load-carriage, and gear connections between said sheave and one of said wheels to propel the carrier at a speed less than that imparted to the load-carriage through the medium of said rope. 20 25

Signed at Seattle, Washington, this 17th day of May, 1919.

ALBIN E. SHODIN.
